United States Patent Office

Des. 211,420
Patented June 11, 1968

211,420

TELEVISION CAMERA

Charles E. Bozarth, Palo Alto, Calif., assignor to Ampex Corporation, Redwood City, Calif., a corporation of California

Filed Oct. 23, 1967, Ser. No. 9,102

Term of patent 14 years

(Cl. D61—1)

FIG. 1

FIG. 2

FIGURE 1 is a front, top and right side perspective view of a television camera, showing my new design; and

FIGURE 2 is a back, top and right side perspective view thereof, the bottom being conventionally plain.

The dominant features of my new design have been shown in solid lines in the drawing.

I claim:

The ornamental design for a television camera, substantially as shown and described.
